UNITED STATES PATENT OFFICE.

ROBERT J. JAUCH, OF FORT WAYNE, INDIANA, ASSIGNOR TO UTILITY STRATE MANUFACTURING COMPANY, OF FORT WAYNE, INDIANA.

SCREW JACK.

Application filed June 18, 1928. Serial No. 286,331.

This invention relates to improvements in screw jacks, especially adaptable for straightening structures that have been damaged or sprung out of their normal form, 5 such as automobile chassis frames.

The object of the invention is to provide an equipment by means of which chassis frames that have become disarranged may be forced back into proper form without dismembering the frame structure.

Another object is to so construct the equipment that it may be applied readily to the chassis frame, and force applied in opposite directions to points more or less remote 15 from each other. And another object is to provide a screw jack equipment with interchangeable extension members by which the length of the jack may be greatly varied as occasion for its use may require.

These objects are accomplished by the construction illustrated in the accompanying drawings, in which:

Fig. 1 is a side view of a screw jack embodying the invention, including a pair of removable extension members, portions being broken away;

Fig. 2 is a fragmentary side view of the screw jack including a different pair of extension members;

Fig. 3 is a similar view showing the screw jack including one of the extension members shown in Fig. 2;

Fig. 4 is a fragmentary view of the screw jack without the use of an extension member;

Fig. 5 is a rear end view of one of the end tips used in the appliance;

Fig. 6 is an elevation projected from Fig. 5; and

Fig. 7 is a plan view of the screw jack applied to a frame as it appears in use, the frame being fragmentary.

The characters appearing in the description refer to parts shown in the drawings and designated thereon by corresponding characters.

The invention consists of an operating member having a head 1 from each end of which extends a threaded stud 2 and 3 respectively, the spiral of the threads on the stud 2 being opposed, as to direction, to those on the stud 3. The head has made therein a series of sockets 4 for the reception of a handle 5 by which the operating member is turned.

Upon each of said studs is a corresponding sleeve 6 that has threaded relation therewith, each sleeve having an external flange 7 at its inner end.

An extension member 8 consisting of a tube 60 is removably positioned upon each sleeve, which sleeve telescopes the corresponding tube, the flange 7 of the sleeve forming a shoulder that bears against the corresponding end of the tube when the latter is in place. In the outer end of each tube 8 is removably positioned a tip 9 having a head 10, the outer end of which is preferably wedge shaped, and with a transverse notch 10' therein, and its inner end 65 being provided with a stud 11 having a series of annular shoulders 12-12' one of which bears against the corresponding end of the tube.

For instances where a jack of greater 75 length is required a pair of tubes 13 are applied interchangeably with the tubes 8, and also there is provided an additional extension tube 14 for each tube 13 which additional tube has telescopic relation with the 80 corresponding tube 13. The tubes 13 have made therein a series of perforations 15, and a pin 16 extends through the tube 14 and through corresponding perforations in the tube 13 whereby the tubes 13 and 14 are 85 held in adjusted positions relative to each other. The perforations 15 in the tube 13 are spaced longitudinally with respect to said tube which admits of securing the tube 14 in various positions upon the tube 13, 90 and in this manner the length of the jack may be varied. When the tube 14 is applied the stud of the tip extends its full length into the outer end of said tube, and the head 10 of the tip bears directly against the adjacent end of said tube.

For instances where a jack of comparative short length is required, the extension tubes 8, 13 and 14 may be dispensed with, in which event the tips may be applied directly to 100 the sleeves with the small ends 17 extending into the outer ends of the sleeves respectively, which ends bear against the shoulders 12' on the studs of the corresponding tips.

In utilizing the invention, the operating 105 member is turned in the sleeves until the sleeves closely approach the head 1, and the tips are applied to the outer ends of the sleeves, or, one or the other of the extension tubes 8 or 13 is placed telescopically onto the 110

sleeves and the tips are inserted in the outer ends thereof. When a jack of intermediate length is required, one of the extension tubes may be omitted. With the parts thus assembled the jack is applied to the frame members 18 and cross braces 19, as indicated in Fig. 7, with the tips inserted at the corresponding junctures of the frame members and braces. By turning the head 1 of the operating member by means of the handle 5, more or less endwise pressure of the jack is exerted between its points of contact with the frame members and braces and with more or less endwise expansion according to the extent 15 the operating member is turned. The jack may be applied in various other positions and to various other objects where force is required in moving objects apart.

The tips being wedge shaped at their outer ends fit more or less snugly in the corners between the side members and braces, and in this manner turning movement of the tips upon their axis is prevented. It has been found that the frictional contact between the tips and their sleeves, or their frictional contact with the extension tubes and the end thrust of the tubes on the sleeves are such, when the jack is in place, that turning movement of the sleeves is prevented 30 as the operating member is actuated.

The outer ends of the tips being wedge shaped, when bearing forcibly against an object, resist turning movement which facilitates manipulation of the operating 35 member.

When the tip is applied to a rod, bead or flange, the notch 10' admits of placing the tip astride of such objects so that turning movement of the tip is thereby prevented.

40 What I claim is:—

1. In a screw jack, an operating member having a head and oppositely disposed threaded studs, the spiral of the thread on the one stud being opposed to that on the other; a sleeve on each of said studs, having threaded relation therewith and being provided at its inner end with an external annular flange; an extension member consisting of a pair of telescoping tubes adjustably 45 and removably connected together, one of

said tubes having telescoping relation with the corresponding sleeve and bearing relation with the flange thereon, there being another similar extension member applicable to the other of said sleeves in like manner; 55 and a pair of tips, each having a head, the inner end of which has a stud provided with a series of concentric shoulders and being applicable to fit interchangeably in the corresponding outer ends of said tubes and 60 sleeve, said shoulders forming corresponding end-thrust bearings therefor.

2. In a screw jack, an operating member having a head and oppositely disposed threaded studs with right and left hand threads respectively; a sleeve on each of said studs having threaded relation therewith and being provided at its inner end with an external flange; a tubular extension member for each sleeve, said extension having 70 telescoping relation with and being removable from the sleeve, one end of said extension having bearing relation with said flange; and tips having corresponding studs provided with concentric shoulders and being applicable to fit interchangeably in the corresponding outer ends of said tubular extensions and sleeves, said shoulders forming 75 corresponding end-thrust bearings therefor.

3. In a screw jack, an operating member 80 having a head and oppositely disposed studs with right and left hand threads respectively; a sleeve on each of said studs having threaded relation therewith provided at its inner end with a shoulder; a tubular extension 85 for each sleeve having telescoping relation therewith, one end of which tube bears against said shoulder; and a pair of tips, each having a wedge-shaped outer end and a stud on its inner end provided with concentric shoulders, said tips being interchangeably applicable to the outer ends of the corresponding tubes and sleeves, the shoulders on said studs forming end-thrust 90 bearings for the corresponding ends of said tubes and sleeve.

In testimony whereof I affix my signature.

ROBERT J. JAUCH.
